COMBINED CURLER COMB AND CLIP

Annie Anthony Coakley, Miami Beach, Fla.

Application June 21, 1954, Serial No. 31,088

Term of patent 14 years

(Cl. D86—8)

Fig. 1

Fig. 2

Fig. 1 is a side elevation of a combined curler comb and clip, showing my new design.

Fig. 2 is a plan view thereof.

Fig. 3 is an end view thereof, seen from the left-hand side in Fig. 1.

I claim:

The ornamental design for a combined curler comb and clip, as shown.
